ABSTRACT: A combination of a telescoping handle, wet mop, broom, dust mop and a storage and carrying case for the same is disclosed. The heads are all interchangeable for use with the same handle and each has its own storage space in the carrier. The carrier is so dimensioned so as to allow storage on a normal kitchen shelf. One embodiment includes an internal cavity for use as a dust pan when the carrier is placed on the floor and in certain embodiments the stowage cavities for one or more of the heads is designed to act as a nonspillable pail and integral wringer.

HOME CLEANING SYSTEM

BACKGROUND OF THE INVENTION

Home cleaning systems employing a broom, dustpan, wet mop, dry mop, pails have changed very little over the centuries. Each performs its individual function and each requires storage space which in many cases is impractical in today's kitchens. This is particularly true in apartments where space can be a premium. The particular difficulties have to do with the stowage of brooms which require a tall space, mops, similarly requiring a tall space, and place to dry the head of a wet mop, pails which require at least a 15 inch depth and 15 inch width area and dust pans which may normally be slipped in beside the cleaning units. The classic storage space is a tall closet having a space of at least 15 inches wide and 15 inches deep and of at least 5 feet in height. Brooms or mops either have to be hung or in the usual case allowed to lean in the corner and tend to fall. In general they all constitute a rather cluttered group when stowed.

Ordinarily, in order to perform a complete cleaning of a room it is necessary to carry each of these members, including water and wax and seldom can they all be carried in one trip.

BRIEF STATEMENT OF THE INVENTION

Faced with this foregoing traditional picture of home cleaning systems, I have devised a completely unitary system making up a common handle usable for wet mop, dry mop, dust mop and broom and all carried in a single easily transported assembly which acts as dust pan, and pail, as well as storage container for all. The carrier is dimensioned so that it fits in a normal kitchen shelf.

With respect to the prior art, the use of telescoping interchangeable head mops and brooms have been known and broom assemblies which carry a dust pan snapped in place adjacent to the head likewise are in the prior art. Collapsible water carriers, for example, small cups have been known in the past to allow storage in a small space. However, none of the above have been combined into a cleaning system of the type herein described.

BRIEF DESCRIPTION OF THE DRAWING

These features of this invention may be more clearly understood from the following detailed description and by reference to the drawing in which:

FIG. 1 is a perspective view of a complete home cleaning system of this invention in its stowed condition ready for placement on a shelf or to be transported;

FIG. 2 is a top view of the system of FIG. 1 with the broom and wet mop additionally visible;

FIG. 3 is an end view of the system of FIGS. 1 and 2 viewed in the direction of the arrows on arrows 3-3 of FIG. 2;

FIG. 4 is a perspective view of another embodiment of this invention;

FIG. 5 is a fragmentary view of the handle of the cleaning system;

FIG. 6 is a top view of the embodiment of FIG. 4;

FIG. 7 is an end view of the embodiment of FIGS. 4 and 6 viewed from the direction indicated by arrows 7-7 of FIG. 6;

FIG. 8 is a perspective view of a typical kitchen cabinet with the home cleaning system stored;

FIG. 9 is a view of the system of this invention being transported for use;

FIG. 10 is an illustration of the system in use as a dust pan and broom;

FIG. 11 is a fragmentary perspective view of the cleaning system being used as a mop and in the integral wringer.

DETAILED DESCRIPTION OF THE INVENTION

Now referring to FIG. 1, the concept of this invention is illustrated by the complete assembly including a storage case and carrier assembly 10 having an integral flat base 11 and an

upper planar surface 12 with a number of cavities 13 to 17 the function of which is described below. The carrier is preferably manufactured of vacuum formed or injection molded plastic in order to be light in weight and sufficient in strength to perform all of its necessary functions. The underside of the carrier 10 is generally hollow.

The recess 13 of the carrier 10 is elongated and dimensions of approximately 2 inches in width, 22 inches in length, and 2 inches in depth. This recess 13 is designed to hold the handle 20 for use with each of the interchangeable heads of the cleaning system.

A broom head 21 is shown positioned in the cavity 15 and a mophead 22 is shown in cavity 16. The cavities 15 and 16 are generally T-shaped in order to provide a recess portion for the stub handle portion of the broom and mopheads.

The cavity 17 may be generally circular in shape and stores a dust mop 23 with its stub attachment 23a.

The cavity 14 in actuality forms a pair of recesses of approximately 4 inches in length and slightly curved and undercut if possible to provide a central hand grip for the carriers positioned to provide a generally balanced load in carrying. Although unshown in the drawing, the carrier 10 may include an integral end grip recesses shown by dashed lines. The hand holes on the assembly are significant in that in one form of operation the carrier is used for transporting water or other cleaning fluids and in that mode the carrier may weigh as much as 7 to 10 pounds.

As is apparent in FIG. 1, the handle 20 includes a number of sections, for example, three which telescope to provide the short length for stowage. The handle includes a locking device 24 designed to mate with the ends of each of the interchangeable heads and hold them rigidly for use and rapid disassembly. An example of a suitable locking device for use in locking the telescoping sections to each other and for attachment of heads is disclosed in the U.S. Pat. No. 3,095,825 to J. W. Sandberg et al., or other types may be used.

It should be noted in FIG. 1 that the two recesses 15 and 16 for the mop and broom head are substantially deeper than is required to hold a single head. This can be used to store more than one head if so desired. Because of the simplicity of the structure, the heads may be disposable after a number of uses and the carrier 10 is therefore designed to hold a number of such disposable heads. It is particularly true that in the case of a wet mop where the head may well be of disposable paperlike material, it may be used only once and thrown away rather than incur the problems of drying before storage. Whether the extra depth is used for storage of additional heads is a matter of choice. If such additional storage is not required the cavities 15 and 16 may be of a shallow depth similar to cavity 17.

The carrier 10 contrasts from most house cleaning carriers in that it has a broad base, low height, and is virtually untippable. This factor becomes significant in connection with the embodiment of FIG. 4.

Now referring to FIG. 2, the carrier 10 of FIG. 1 and particularly the placement of the handle and head assemblies is clear. The cavities 13, 15, 16 and 17 are each dimensioned to hold their respective cleaning system component and it is readily apparent when any part is missing. The integral handle 14 is shown positioned in the planar surface 12 between the recess 13 and the line of recesses 15 and 17. It is of course recognized that the exact position of the recess 14 is determined by the proper balance to allow the assembly to be carried comfortably in one hand.

The height of the carrier 10 and the relative depth of each of the recesses is apparent from FIG. 3. In the embodiment of FIGS. 1, 2 and 3 the unit has a height in the order of 6 inches and a width in the order of 15 inches. The overall length of the carrier is in the order of 24 inches. This dimension is compatible with most kitchen shelves allowing the entire assembly to be stowed out of sight without taking any floor or closet space. As shown in dashed lines in FIG. 3 the cavities 13, 14 and 15 extend below the surface 12 leaving substantial void area below. The cavity 15 is of sufficient depth to hold two or three

broom heads if desired. It should be noted particularly from FIG. 3 that the base 11 is quite broad and the sides slightly tapered upward to produce a stable geometric shape. In the embodiment of FIGS. 1 through 3, the compatibility of assembly with drawer or shelf space is of prime concern. For that reason it is rectangular in shape and height in the order of 6 inches to allow its accommodation by most small shelves. It is apparent in the view of FIG. 3 that there is a substantial hollow area within the carrier 10 and this volume is utilized in accordance with the embodiment of FIG. 4.

Now referring to FIG. 4, a carrier 30 having a slightly greater height than the versions of FIGS. 1 through 3 may be seen including a handle recess 31 and a pair of recesses 32 and 33 for holding broom and mopheads along with a recess 34 for a dust mop. Handle recesses 35 similar to those in FIG. 1 are included and an additional recess 36 for carrying other cleaning materials is present. As an example, the recess 36 is shown generally rectangular in shape but with a slight concave wall whereby the recess may accommodate both rectangular boxes of cleaning material and oval or round bottles or cans as well. One of a pair of integral end handles 37 is shown.

One significant difference in this embodiment is apparent in the front face where an additional recess 40 is present having a front ramp 41 which ends at the base or floor level of the carrier. The ramp 41 has a ridge 42 and an inner ramp 43 tapered inward and down toward the interior of the housing 30. This cavity 40 constitutes a receptacle for sweepings when the system is in use. The ramp 41 is preferably integral with the outer base 44 of the carrier 30 and the lower lip is designed to maintain contact with the floor surface whenever the carrier is at rest. This cavity and ramp region constitute an integral dust pan in the carrier which cannot become separated from the remainder of the cleaning system and which accompanies the cleaning system with no additional effort. The cavity 40 is fairly large in the order of 20 inches across allowing for a large capacity stowage of sweepings without the repeated emptying step when using conventional dust pans. It is the intention that the cleaning system can be transported to a room and that the carrier has all the material necessary for a normal cleaning function; and when the carrier is removed from the room, it takes with it all cleaning materials, brooms, mops and sweepings.

It should be noted in FIG. 4 that the two recesses 32 and 33 are shown providing an additional function compared to FIGS. 1 to 3. The recesses 32 and 33 extend nearly to the floor or may extend fully that far and are of sufficient volume to constitute a small water or other cleaning fluid carrier. The two recesses can be used for wash and rinse water, side-by-side without the necessity of emptying the pail and refilling. Moreover, the T-shape of the cavity designed for easy stowage and carriage of cleaning heads also is valuable as will be illustrated later in connection with FIG. 11. The carrier 30 has a raised edge 30a designed to prevent water drippage from the upper surface. The cavity 31 is shown as holding a handle 20a in its telescoped condition.

For simplicity sake, an external threaded end attachment of handle 20 is shown in this embodiment since most standard mop and broom heads accept threaded handles. This would allow the use of different heads for the handle for use with other types of appliances in addition to those furnished with the system.

The appearance of the handle 20a in its extended position is shown in FIG. 5. It includes three telescoping sections with a handle grip at the opposite end and external threads at the lower ends. Internal locking in the three sections are unshown in the drawing and are preferably as shown in the Sandberg patent. This locking system is particularly advantageous since it is easily locked and unlocked and allows the handle to be 70 locked at any length.

The entire system of the embodiment of FIG. 4 is shown in FIG. 6 with the handle 20a stowed in recess 31. A broom head 50 is stowed in recess 32, and mophead head 51 is stowed in the recess 33. The mop strands may be folded underneath the 75

head in the manner shown. A dust mop 52 is shown stowed in recess 34.

The FIG. 7 clearly illustrates the details of the dust collector cavity 40 with its exterior ramp 41 and lip 42 and interior ramp 43. Also the relative size of the cavity 32 is apparent. Since the cavity 32 is in the order of 8 inches deep, 8 inches wide and extending 6 inches from front to rear, it has a volume of at least $\frac{1}{4}$ cubic foot. This cavity 32 will therefore hold in the order of two gallons safely without the danger of spillage. The cavity 40 is also relatively large so that it can accommodate all the sweepings that might normally be encountered in a single cleaning operation.

The mode of storage, plus the modes of use of the system are illustrated in FIGS. 8 through 11. In FIG. 8 the system is shown on the shelf 60 of a kitchen sink assembly 61. This is a normal storage area which is usually available in virtually all homes and one which is not necessarily used to the best advantage. The system is also dimensioned such that it may be stored in relatively large kitchen drawers such as drawer 62 by placing the assembly length wise in the drawer rather than transverse position as shown on shelf 60.

The system in transport is illustrated in FIG. 9 with the user carrying the system by a central handle. This is desired where the cleaning materials are being carried without any water or cleaning fluid. The central handle is adequate for such normal transportation of the carrier 10. End handles 37, one of which is shown, will be used for transporting the system when it is used for carrying water as well.

The FIG. 10 illustrates the system in use with a broom in which the sweepings are directed towards the carrier 30 which rests on the floor. The weight of the entire system is sufficient in that there is little danger of the carrier moving on contact with the bristles of the broom and no danger of tipping.

Another significant advantage of this invention is illustrated in FIG. 11 where the system is used for mopping. The carrier cavity 32, in this case, is filled with water and the mophead 51 is in place on the handle 20. The cavity 32 is used as a pail; and because of its unique shape, has a narrow portion at one side and the width corresponds approximately with the width of the mophead 51. Therefore the mop may be dunked into the cavity 32 in the normal manner and by twisting the mop as it is drawn out of the cavity 32, the mop strands fall into the T portion 32a and with further twisting and withdrawal of the mop the strands are wrung through the T-shaped opening. This arrangement constitutes an integral pail and wringer for the mop. When the cleaning operation is finished the carrier may be transported to a sink or other receptacle and by tipping the carrier first in the direction of arrow "a" in the drawing, the liquid contents may be emptied out of the cavity 32 and cavity 33 if it so used. When the liquid contents are removed, the carrier may then be tipped in the direction of the arrow "b" and the sweeping contents of cavity 40 emptied. After such action the system is ready for disassembly and storage. Where the wet mophead is stored in the carrier any drippings fall into the cavity 32 or if the mophead 51 is discarded the head may be used in the next operation.

The foregoing is a description of two embodiments of this invention and are not all inclusive of any modes of construction or operation of the invention. It is recognized that one skilled in the art, can through minor modification of the structure produce a device different in certain details and respects but not departing from the true spirit and scope of the invention. This invention therefore is not limited by the embodiment shown above but rather than by the prior art and the following claims.

1. A cleaning system comprising:
an extendable retractable handle,
a plurality of interchangeable heads for said handle to perform different cleaning functions,
carrier means for said handle and heads comprising a body having height and width approximating normal kitchen shelves including recess means for the interchangeable heads and a separate recess for storing the retracted handle,

said carrier means being dimensioned to rest on a shelf or in a drawer and having at least one of the aforementioned recesses in the upper surface and of sufficient size to constitute a holder for cleaning fluids for use with the system when the recess is not occupied by a head or handle.

2. The combination in accordance with claim 1 wherein said carrier means includes at least one hand hold to allow the transporting of the entire cleaning system by said hand hold with said carrier means.

3. The combination in accordance with claim 1 wherein said interchangeable heads include at least a broom and a mop having generally T-shaped heads, the handle and heads including mating locking devices whereby the heads may be selectively attached to the handle.

4. The combination in accordance with claim 1 wherein said recesses are of sufficient depth to hold more than one interchangeable head.

5. The combination in accordance with claim 1 wherein said carrier includes an additional side recess adjacent to the lower outer edge including a ramp portion and an internal cavity suitable for use in dust collection by sweeping dust over the ramp into the cavity.

6. The combination in accordance with claim 1 wherein said recess includes a restricted portion in one of the edge walls which acts as an integral mop wringer.

7. The combination in accordance with claim 6 wherein said recess usable for cleaning liquid is generally T-shaped to accommodate the T-shaped head and the narrow portion of the T constitutes the integral mop wringer.

8. The combination in accordance with claim 1 wherein at least two of the recesses are of sufficient depth and closed bot-

tom to provide two cleaning liquid storage areas, for example, one for wash and one for rinse water.

9. The combination in accordance with claim 4 wherein said carrier includes an additional recess dimensioned to hold a package of cleaning compound.

10. A storage and carrier assembly for cleaning equipment comprising a unitary body of material unaffected by cleaning solvents including a generally flat base and dimensions compatible with a shelf storage area, said body including a plurality of recesses adapted to hold a handle and a plurality of interchangeable cleaning heads.

11. The combination in accordance with claim 10 wherein said unitary body, generally rectangular in shape, with a planar top surface and the plurality of recesses in the planar top surface in a horizontal position.

12. The combination in accordance with claim 10 wherein said unitary body includes at least one recess in the sidewall constituting a cavity for the retention of floor sweepings and the lower edge of the cavity includes a ramp portion providing an incline surface for entrance of sweepings.

13. The combination in accordance with claim 10 wherein at least one of the recesses in the upper surface is T-shaped and is of sufficient dimensions and depth to hold a cleaning liquid for use with one or more of the interchangeable cleaning heads.

14. The combination in accordance with claim 13 wherein said T-shaped recess includes the body of the T portion presenting a constricted exit for a mop whereby removal of the mop via the constricted portion results in at least a partial wringing of the mop.
